HEAT EXCHANGING SYSTEM

John B. Gaudin, New York, N. Y.

Application December 31, 1935, Serial No. 56,945

4 Claims. (Cl. 257—141)

This invention relates to heat-exchanging systems, especially to radiator devices for use in such systems, and more particularly to a known type of radiator characterized by so-called "fins" usually comprising thin sheets of metal associated in heat-conducting relation with more compact heated conduits or bodies, and so disposed as to transfer the heat therefrom to the surrounding atmosphere or other fluid environment.

10 The efficiency secured in systems including fin-type radiators so constructed leaves much to be desired, and the problem of increasing this efficiency, while retaining the desirable structural features characteristic of the fin-type radiator unit, has been the subject of prolonged

15 research and experimentation by heating engineers, with results not entirely satisfactory.

As the outcome of my own investigation of this problem, I have discovered that a prime obstacle 20 to economical transfer of the heat available under such conditions is to be attributed to inefficient provision for rapid heat conduction in the vicinity of the central conduit for the heating medium, this being due to the small mass 25 of the metallic body at the region of the connection between the fins and the conduit, so that the heat has been so sluggish in its emergence to the space to be heated that the advantage of the fin-type members has been practically lost.

30 The general object of the present invention is to provide, in a heating or heat-exchanging system of the class described, and in which fin-type radiators are employed for the sake of their characteristic advantages, various improvements in 35 structural form of the component elements of the typical fin-type radiator unit, and also improvements in the co-ordination of such fin-type units as co-operating instrumentalities for the transfer of heat to the space to be heated, which 40 improvements will obviate to a great extent, if not entirely, the aforesaid disadvantages, and will advance the performance of the fin-type radiators toward their optimum degree of efficiency and economy.

45 In pursuance of this general object, an object of the invention is to provide a laminated, tubular, heat-conducting body, along the entire longitudinal axis of the radiator, adapted to yield rapidly to the fins a maximum amount of the 50 heat carried by its fluid heating medium, and another object of the invention is to avoid entrapment of heat centrally within the fins; also, as a means to this end, to provide for the better circulation of air in the interstitial spaces of the

assembly of fins, and for the freer flow of said air therefrom after it shall have been heated, with more rapid, more uniform, and more complete, transfer of the heat so communicated to this circulating air, such heat transfer being greatly improved by my novel arrangements herein disclosed, inasmuch as the air is caused thereby to flow rapidly between the heated fins, and to flow therefrom into the circumambient atmosphere of the space to be heated, to which the 10 heated air in transit acts to transfer its heat by the known and reliable operation of convection and diffusion.

A cognate object of the invention, in pursuance of the aforesaid general object, is to effect such a change in the physical structure of the fin components as to provide a novel, shorter path for transfer of heat from the center of the fin structure to the periphery thereof by direct, metallic conduction, this path being provided in 20 the form of sheet-metal complementary fins lying in planes substantially parallel with, and contiguous to, other, fluted fins which are disposed in a series the members of which extend radially from the axial conduit of the conduit, i. e., at 25 right angles thereto, the flatings of the last-named series co-operating with the flat surfaces of the fins in the complementary series to form channels or flues having at each end openings to the space to be heated.

30 Another object of the invention is to provide a novel form of conduit to be included in the service line for conveying steam or other heating fluid to the fins assembled thereon, and which is of such contour or cross-section as to reduce the 35 discrepancies in the lengths of the paths by which heat is conducted metallically from the centers to the margins of the fins. Such an improved conduit may take desirably the form of a rather flat elliptical or oblong tube, i. e., one 40 that is sensibly oblong in cross-section.

45 Among other objects of the invention are the provision of improved means by which the novel fin-type radiator structure embodying the several features already disclosed briefly, and to be described more at length hereinafter, may be supported in use, and co-ordinated with the service conduits of existing heating, or heat-exchanging, systems, to which it is desirable that my improvements shall be applicable without 50 essential disturbance of those systems, and among such adapter means are included header and coupling devices to be described.

55 Other objects and advantages will appear as the description of the particular physical em- 55

bodiment selected to illustrate the invention progresses, and the novel features of the invention will be particularly pointed out in the appended claims.

5 In describing the invention in detail and the particular physical embodiment selected to illustrate the invention, reference will be had to the accompanying drawing, and the several views thereof, wherein like characters of reference designate corresponding parts, and in which:

10 Figure 1 is a view in plan, partly in horizontal section, of a fin-type radiator in the construction of which the present invention has been embodied;

15 Fig. 2 is a plan view of a modification;

Fig. 3 is a view in vertical section on the line 3—3 of Fig. 1;

Fig. 4 is a view in elevation of one of the planiform fin elements taken separately;

20 Fig. 5 is a fragmentary, detail view of the header parts and central conduit, in assembled relation, and taken separately from the fin components;

Fig. 6 is a detail view in front elevation of one 25 of the header parts, taken separately; and

Fig. 7 is a similar detail view of the complementary header part, also taken separately.

In a now-preferred embodiment of the invention selected for illustrative disclosure herein, the 30 part designated by the reference character 11 is a conduit, preferably made of copper, or of an alloy of copper, on account of the superior heat-conductivity, resistance to corrosion, and other desirable properties which qualify that metal for 35 use in systems intended to circulate fluids for household heating, for refrigeration, and for heat-interchange in many of its other applications; and in pursuance of an important feature of the present invention, to which a brief reference has been already made, this conduit is preferably characterized by having an oblong cross-section, or one that is generally elliptical in contour, the primary object of such formation of the conduit being to permit the assembly there- 40 with of fins having a rectangular, or other non-circular contour which facilitates optimum occupation usefully of a given cubical space, while preserving the advantages of uniform radius of direct metallic heat-conduction which has been 45 heretofore characteristic only of flat circular fins 50 associated with a central conduit of circular cross-section.

In the structure illustrated herein, merely by way of example, I have provided two series of fins, 55 preferably made of the same material, i. e., of copper, or a copper alloy of suitable composition, having due regard to the necessary thinness of the sheet metal of which the fins are composed, the several members of these series respectively 60 being designated by the reference characters 12 and 13, the latter numeral being applied to each of a series of fin members or components characterized by having the form of flat plates, or having 65 a general planiform conformation; the components of the other series being characterized by a fluted conformation; and the components of both series having a common, rectangular form, substantially oblong, in the instance illustrated, this not being intended, however, to exclude the 70 use of other non-circular shapes.

The flutings c of the fin components 12 may be desirably made in a zig-zag conformation, as shown clearly in Figs. 1 and 3, and this fluting resembles conventional fluting of such fins in 75 general contour, but differs preferably there-

from substantially in various features which I have discovered to yield improved efficiency of a very high order in the transmission of heat between the contiguous walls of the fins and the fluid medium, such as air, circulated thereover.

One of these differences resides in the sharper pitch of the walls c, as compared with earlier types of fluted fins, and I secure thereby an increase in the area available for heat-exchange within a given cubical space, as compared with 10 the known types of fluted fins. Another difference emerges in the shape of the walls, as clearly seen in Figs. 1 and 3. The walls c run from end to end of the fluted fin of my novel type, and a series of long, parallel, vertical channels or flues 15 F is thus provided, in which the circulated air or other fluid may flow with uninterrupted continuity, promoting optimum heat-exchanging efficiency.

These flues, in fact, are of ideal form to co-operate in imparting to the ascending air the kinetic energy derived from the heated conduit 11, and so hastening its speed of circulation, for no space whatever is wasted, and there are no regions where the upward draft is materially checked. 25 The channels of narrowest cross-section are those at the lateral margins, and those near the middle, and all of the other flues may be of approximately double the cross-section of the outermost lateral flues, as is clearly shown.

30 The innermost are only constricted at the region of greatest heat, namely, along the straight sides of the tube 11, and it is desirable that the swiftest flow of air shall occur at this region, which is in fact the case, so that in this respect 35 my novel disposition of the walls with their flue-like contour is more correct theoretically than the disposition provided for by known types of fin radiators.

40 In pursuance of what may be regarded as the underlying object of the present invention, i. e., the creation and maintenance of direct metallic conduction of heat from the tube 11, which is its prime source within the radiator, in the instance 45 illustrated, and in order to effect equalized transfer of this heat to the circumambient atmosphere of the space to be heated, I have provided, in the series of fin elements 13, a heat-conductive instrumentality which is novel, both in the idea of means which it embodies, and in its combinative 50 relationship with the better known fluted-type fins 12.

The fins 13 are formed separately from the fins 12, and each fin 13 comprises a plate or planiform body part, which is preferably of rectangular or other non-circular form, and desirably of approximately the oblong shape shown in Fig. 4, and it is illustrated as having marginal flanges 13' suitably spaced apart to receive between them, and to fit over, the outer marginal edges 12' of the fluted fin components 12, as shown in Figs. 1 and 3.

55 The fin components of each series are severally provided with body orifices respectively, so that they can be assembled in tandem relation upon the conduit 11. As illustrated, these orifices are surrounded by hollow bosses 12'' and 13'' respectively, of which the bosses 13'' are the smaller, being adapted to fit snugly upon the conduit 11, as shown in Figs. 1 and 3. The latter figure shows 60 also how the bosses 12'' fit snugly upon the bosses 13'', and preferably each of the bosses is slightly coved, as indicated at c', in Fig. 4, so that they 65 may be more readily assembled with a force fit upon the conduit 11.

In so assembling them, it is convenient, first, to force a planiform fin component of the series 13 upon a conduit 11 of suitable size, and then to force a fluted fin component of the series 12 into the position shown near the left-hand end of Fig. 1, its boss 12" being forced upon the underlying boss 13"; so that there is at that region a triple-laminated, heat-conductive wall or body in which the concentric bosses re-inforce the underlying parallel conduit walls, and act as complements thereof for creating a primary heat-transfer body or agency of desirable mass. This is a novel provision of my present invention, and is so claimed generically, except when particular claims are specifically limited.

Reverting now to the assembling operation, it will be noted that the outer wall-portions 12' find their way automatically into the nested relation illustrated in Figs. 1 and 3, within and confined by, the flanges 13', with which and the body part 13 they form marginal channels of right-angled triangular cross-section.

Thus a fluted fin component 12, and its complementary planiform fin-component 13 may be considered to constitute a compound fin; and each successive compound fin so constituted may be conveniently installed by forcing its members into place seriatim; although this suggestion is not intended to exclude the adoption of any other convenient procedure in fabricating an assembly of the type illustrated.

Again, the closely set relationship of adjacent compound fins, as illustrated in Fig. 1, has the desirable effect that the body part of each succeeding planiform fin component serves in a complementary fashion to complete the structure of the triangular channels or flues F whose other two walls are formed by flutings of the fluted fin component.

Furthermore, the planiform body portions 13, which derive heat by metallic conduction directly from the relatively long, parallel, mutually contiguous areas of contact between their bosses 13" and the underlying conduit 11, are, by virtue of the radially extending, unbroken body portion 13, of each such component, endowed with a novel characteristic capacity to transfer heat by metallic conduction over the shortest possible route toward the periphery of the radiator.

As the distances radially from the axially disposed oblong tube 11 are substantially equal for each point on the periphery, which equality clearly appears from the showing in Fig. 4, it is evident that I have provided for a more uniform distribution of conducted heat than has heretofore been possible with the use of such fin-type radiators as have utilized round conduits and square fins, even when the fins were corrugated.

The disposition of these compound fins in contiguous relation with each other according to my invention, serves an extremely important further purpose, moreover, in that the heat in course of transfer from the core to the periphery of the radiator structure, is tapped off from the planiform fins by the fluted complementary fin components at all such regions of contact therebetween as are designated by the reference characters c.

Without elaborating the description of this service, which is readily understandable from the disclosure in the drawings, it will suffice to say that, not only does heat travel laterally from the flat wall portion of conduit 11 along the tortuous path afforded for metallic conduction by the zig-zag walls of the flutings, but at each linear con-

tact, as c, the fin component 12 receives from the fin component 13 an increment of heat by direct metallic conduction. This heat-increment has only travelled over one-half of the distance from its source that must be travelled by heat conducted over the tortuous path, and is thus adapted to reinforce the heat available for the member 12 to carry to its further reaches, and so a desirable and novel transfer and equalization of heat is effected until, by the time the periphery of the 10 radiator is reached, substantially all of the heat units which were available for transfer to the currents of air circulated upwards through the flues F between the fin components has been so transferred, and the transfer has been accomplished in the most efficient manner because none of the available heat has been entrapped or lost.

Again, it will be noticed that each flue is formed by two walls of fluting and one, relatively flat, wall formed by the flat fin, so that the combined heat 20 made available by each type of conduction is effectively distributed throughout the radiator.

It is evident that the size of the radiators can be extended to an indefinite length, within practical limits, according to the requirements of 25 individual installations, and that no separately formed boundary wall members have to be provided at the margins, since the abutting end-flanges of the fin components 13 constitute a virtually continuous flat surface.

As the fin components are desirably made of copper, the same material as that of the central heat-conducting tube 11, the longitudinal expansion and contraction of the system is self-compensating throughout, and does not set up deleterious internal tension, so that no undue strain 35 is imposed upon the conduit, nor is there undue compression of the fin components. If extreme conditions of heat should supervene, conceivably the expansion of the fluted members 12 might 40 force the flanges 13' outwardly and cause a telescopic readjustment to take place as between adjacent compound fins, but without harm to the system. Such telescopic arrangements are within the scope of the underlying idea of means, and 45 in general the particular physical embodiment disclosed is to be regarded as illustrative rather than limitative.

Wide range is possible in the selection of fittings and as a convenient and now-preferred 50 form of fittings I have shown at each end of the conduit 11 a fitting which is desirably simple, but efficient for the intended use, as it affords a practical means for connecting such a radiator with the domestic heating pipes of a dwelling, or in 55 any other heat-exchanging system for which the system of fin-type radiator embodying my improvements may be available.

Each fitting includes a female part 21 and a male part 22, these parts having complementary 60 surfaces adapted to be fastened together by bolts 23, leaving, as at 24, a slight clearance conforming in general contour to the end of conduit 11, which is desirably flared, as at 11x, to be clamped in the manner shown in Figs. 1 and 5. The 65 member 22 has a nozzle 25 suitably threaded for attachment to the domestic supply pipe for steam, hot-water or other heating or cooling fluid, according to the intended use of the system.

Other forms of fittings may be utilized, as will 70 be readily apparent to those skilled in the art.

An example of a modified form of heater unit, adapted to yield increased radiating surface without corresponding increase in length, where such increase in length might be undesirable, is shown 75

in Fig. 2, where the compound fin elements F' may each be considered to embody a fluted fin, as 12, and a flat fin, as 13, combined and co-operating as already described with respect to the parts so designated in the structure disclosed in Figs. 1 to 4.

Each compound fin in this modification is, however, of greater dimension transversely of the radiator assembly, than are those shown in Fig. 1, and the modified assembly is arranged to be heated by two stretches of conduits 11A and 11B, which are assembled with the fins in a manner like that already described at length, except that each fin component has two oblong bosses, arranged in parallelism, as will be readily understood from the disposition of the dot-dash lines designated by the reference characters 11A and 11B in Fig. 2, without further illustration.

Each fitting for this modification comprises a female part 21' with two openings each registering with an end of one of the tubes 11A and 11B respectively; also a male part 22' is provided, having portions similar to those of the male member 22 of Fig. 1, adapted to hold the ends of the tubes 11A and 11B, as the case may be, in a clearance like that indicated at 24 in Fig. 5.

The parts 25' may be formed as manifolds of conventional form, and it will be understood that the irregular lines in Fig. 2 are intended to indicate indefinite extension horizontally of the units, which will be governed by considerations of convenience, economy and economy in operation, just as in the Fig. 1 form of the invention.

There may be as many of the central tubes, like those indicated at 11A and 11B as may prove to be desirable in accordance with the requirements of any given installation.

Instead of a tubular conduit for heat-conducting fluids, the member 11 may be substituted by an elongated heat-conductive body of any suitable character, as, for example, an electrically energized resistor element of any suitable character and contour.

I claim:

1. A heat-exchanging appliance for a heat-exchanging system of the class described; said appliance having the features claimed in claim 4, and in which the heat-conductive member is made as a thin, sheet-metal conduit for fluid, and said fins are respectively polygonal in shape, the flutings and contiguous radial body portions forming parallel vertical flues between the fins and open from end to end of the fins, whereby a heat-transferring fluid may be circulated in said flues in such a manner as to be discharged forcibly therefrom to a circumambient body of fluid.

2. An assembly of fin elements in a heat-ex-

changing appliance of the fin-type; said assembly comprising a set of complementary fin elements, one having a fluted body portion and another having a planiform body portion with which said flutings co-operate to constitute furrows; and each of said elements having a hollow boss serving to support said elements in complementary relative position and in heat-exchanging fitment upon an elongated heat-conductive member common to both of said elements, said bosses overlapping each other throughout the inter-fin spaces and constituting, with the underlying portions of said heat-conductive member, a triple-laminated structure.

3. An assembly of fin elements in a heat-exchanging appliance of the fin-type; said assembly including an elongated heat-conductive member of substantially oblong cross-section extending to an indefinite extent along the major axis of the appliance; and a plural series of fin elements, the members of the two series being arranged in alternating disposition, the members of one series respectively having planiform bodies, and the members of the other series respectively having fluted bodies, whereby said elements co-operate to form flues therebetween, and the respective fin elements each having a boss surrounding said elongated member, said bosses overlapping each other throughout the inter-fin spaces and constituting, with the underlying portions of said heat-conductive member, a triple-laminated structure.

4. A heat-exchanging appliance for a heat-exchanging system of the class described; said appliance having an elongated heat-conductive member, and pairs of radiating fins with complementary bosses arranged in contiguous, abutting series along said member, one fin-component of each pair comprising one of said bosses fitted closely upon said member, extending along the same for the entire width of the pair, with a radially disposed, integral body portion of sheet metal, and another, complementary fin component having a boss fitted closely upon said first-named boss with an integral body portion of sheet metal having zig-zag flutings disposed between, and contacting with, the radially disposed body fin of the same pair and the radially disposed body fin of an adjoining pair, whereby said elongated member constitutes, with said superimposed bosses and the integral portions angularly connecting the bosses with their respective fin body portions a unitary, triple-laminated heat-conductive central metallic structure which may be extended to any desired extent lengthwise by the addition of similar complementary pair components in alternating order.

JOHN B. GAUDIN.
